GEORGE R. HUBBARD, OF NEW YORK, N. Y., ASSIGNOR TO BRADLEY & HUBBARD, OF WEST MERIDEN, CONNECTICUT.

Design No. 4,814, dated April 18, 1871.

DESIGN FOR A MATCH-SAFE.

The Schedule referred to in these Letters Patent and making part of the same.

To all whom it may concern:

Be it known that I, GEORGE R. HUBBARD, of New York, in the county of New York and State of New York, have invented a new Design for Match-Safe; and I do hereby declare the following, when taken in connection with the accompanying drawing, to be a full, clear, and exact description of the same, and which said drawing constitutes part of this specification and represents a side view, the broken lines showing the cover raised.

This invention relates to a design for match-safe, and consists in a box, in shape representing a frog at

rest, the head raised by the forward legs, and the body divided through the mouth to the tail, where the hinge is formed, so that the upper part rises, as denoted in broken lines, the lower part forming the receptacle for the matches.

I claim as my invention—

The design for match-safe as herein described, and illustrated by the accompanying drawing.

GEO. R. HUBBARD.
